(57) **CLAIM**

The ornamental design for a connector ring, as shown and described.

DESCRIPTION

FIG. 1 is a rear perspective view of a connector ring showing our new design;

FIG. 2 is a front view thereof;

FIG. 3 is a rear view thereof;

FIG. 4 is a top plan view thereof, bottom plan view being a reversed image thereof; and,

FIG. 5 is a right side elevational view thereof, left side elevational view being a mirror image thereof.

1 Claim, 3 Drawing Sheets

*FIG. 1**FIG. 2**FIG. 3*

FIG. 4

FIG. 5
